EYEGLASS DISPLAY SUPPORT POST

Richard S. Dunchock, Northville, Mich., assignor to
Optarac Corporation, Ferndale, Mich.

Filed Aug. 19, 1974, Ser. No. 498,543

Term of patent 14 years

Int. Cl. D6—06

U.S. Cl. D6—191

Fig-1

Fig-2

Fig-5

Fig-3

Fig-6

Fig-4

FIG. 1 is a perspective view illustrating an eyeglass display support post showing my new design;

FIG. 2 is a top elevational view thereof;

FIG. 3 is a left-end elevational view thereof and is identical to the right-end elevational view which is not shown;

FIG. 4 is a bottom elevational view thereof;

FIG. 5 is a rear elevational view thereof; and

FIG. 6 is a front elevational view thereof.

I claim:

The ornamental design for an eyeglass display support post, as shown and described.
